UNITED STATES PATENT OFFICE.

RALPH NELSON GEFFROY, OF NEW YORK, N. Y.

ENVELOPE.

Application filed October 6, 1922. Serial No. 592,800.

To all whom it may concern:

Be it known that I, RALPH N. GEFFROY, a citizen of the United States, and a resident of the city of New York, borough of 5 Manhattan, in the county and State of New York, have invented a new and Improved Envelope, of which the following is a full, clear, and exact description.

This invention relates to improvements 10 in paper receptacles, and has particular reference to an envelope.

Heretofore the manufacture of envelopes has entailed a large waste of paper due, not so much to the quantity of paper used in 15 forming each individual envelope, but to the configuration of the blanks of which the envelopes are made and which are cut from one continuous sheet. In the ordinary construction of envelopes each blank consists 20 of a body forming the front of the envelope, two side flaps, and a bottom flap, which are folded to provide the back of the envelope, and a closure or top flap employed to seal the envelope. When cutting the blanks of 25 such envelopes the bottom and closure flaps are of substantially the same configuration to the extent that their greatest transverse width is at the central portions thereof. Due to this construction it is necessary to 30 cut the blanks from the continuous sheet in staggered relation to each other and in so doing considerable paper is wasted in forming the flaps and particularly the bottom flap.

In accordance with the present invention 35 the blanks are formed from a continuous strip of material of a width equal to that of one envelope and, in contradistinction to the above method of cutting the blanks in 40 staggered relation to each other, the successive blanks are aligned and the bottom flap of each blank is formed by the cutting of the closure or top flap of the next adjacent blank so that the cutaway portion or 45 free longitudinal edge of said bottom flap is of the same configuration as the free edge of said closure flap. This results in the bottom flap having its greatest transverse width at the ends thereof and the closure 50 flap having its greatest width at the central portion thereof. Also in forming the blank the front and bottom flaps are made of the same width, whereas the closure flap is of less width than said front and bottom flap, 55 the closure flap being formed by simply cutting away a very small portion of the

strip at opposite points thereof between the closure flap of one blank and the bottom flap of a next adjacent blank. By thus forming the bottom and closure flaps it will 60 be obvious that practically no waste of paper will result from the cutting operation.

It has also been heretofore suggested to provide a line of perforations adjacent and parallel to the ends of an envelope and to 65 secure reinforcing strips to said ends to facilitate the opening of the envelope when removing the contents thereof. In known constructions of this character, and notably the patent to Denson, No. 750,350, dated 70 January 26th, 1904, wherein perforations are used, it has been found that considerable difficulty is experienced in severing the ends of the envelope along the lines of such perforations, due to the fact that perforations are insufficient to provide an adequate 75 tearing line, particularly when it is necessary to sever the end sections of the envelope which are formed by the front and side flaps thereof, in addition to those portions 80 of the bottom and closure flaps which overlap said side flaps. With such a construction it oftentimes occurs, that in severing an end section the tearing will not follow the line of perforations, but will include portions of the body of the envelope as well with the ensuing possibility that the contents of the envelope will be torn if proper care is not exercised. Also with an envelope 85 as shown in the above mentioned patent, 90 wherein a reinforcing strip or band is secured to each end section of the envelope there is nothing to prevent the contents of the envelope from working outwardly or endwise beyond the line of perforations and 95 under the reinforcing strip during the passage of the envelope through the mails, so that unless the recipient thereof first forces said contents into one end of the envelope and clear of the other end thereof, the 100 probability is that said contents will be torn when severing the latter end. Furthermore by securing a reinforcing strip or band over each end section of the envelope, as shown in said patent, it is apparent 105 that the edges of said strip will project beyond or be offset from the adjacent faces of the envelope, thus rendering said strips liable to accidental tearing and possibly complete severing as the envelope is more 110 or less frequently handled in the mails.

An object of the present invention is to

overcome the above mentioned difficulties and at the same time secure all of the advantages incident to a construction of the character referred to by forming an end of 5 the envelope with a tearing line that is produced by interlocking the sheets comprising the body of the envelope and at the same time interlocking the edges of the reinforcing strip with said sheets and with each 10 other, so that the portion of the envelope along the tearing line will present a substantially smooth surface, thus obviating the possibility of an accidental tearing or severing of said strip.

15 Another object is to provide an improved tearing line which is so formed that the contents of the envelope will be prevented from moving endwise thereof beyond said line so that when the end section of the envelope 20 is severed, said contents will be free from any possibility of accidental tearing.

A further object is to reduce to a minimum the waste of material resulting from the cutting of a blank.

25 The above and other objects will appear more clearly from the following detail description, when taken in connection with the accompanying drawing, which illustrates a preferred embodiment of the inventive idea.

In the drawing—

Figure 1 is a plan view of an envelope constructed in accordance with the invention;

35 Figure 2 is a vertical transverse section through the envelope;

Figure 3 is a fragmentary plan view of the continuous strip from which the envelope blanks are cut and illustrating the 40 formation of the blank of each envelope;

Figure 4 is a greatly enlarged section on the line 4—4 of Figure 1, showing the manner of interlocking the sheets comprising the body and reinforcing strip of the 45 envelope;

Figure 5 is a fragmentary enlarged plan view of an end section of the envelope showing the tearing line therefor; and

Figure 6 is a section on the line 6—6 of 50 Figure 4.

Referring to Figures 1 to 3 and more particularly to the latter figure, it will be seen that the envelopes are formed from a continuous strip of material, such as paper, 55 which is of a width equal to that of the entire envelope and that each blank is in direct alignment with the next adjacent blanks. The body or front 7 of each blank is defined by the dotted lines 8, the ends 60 of the inner face of which are gummed, as indicated at 9, so that when the blank is folded to form the envelope the ends of the bottom flap 10 may be secured to the front 7. The bottom flap 10 is formed by 65 cutting the material along the transverse

line 11 which extends transversely of the strip of material and which also defines the free longitudinal edge of the top or closure flap 12. Said edge of the closure flap and the similar edge of the bottom 70 flap will be of the same configuration. The free longitudinal edge of the closure flap 12 is also gummed as indicated at 13 so that the envelope may be sealed for mailing. In forming the blanks 75 the material along each longitudinal edge of the continuous strip is cut away, as indicated at 14, at points contiguous to adjacent bottom and closure flaps so that the latter flaps will be of slightly less width 80 than the body of the envelope, as clearly illustrated in Figure 1, thus forming extensions at each end of the envelope which are of substantially the same width as the gummed portions 9. In addition to gluing 85 the bottom section 10 to the front 7 the ends of the envelope are further closed by means of reinforcing strips 15, which, when folded over the ends, are of the same width 90 as the gummed portions 9.

In carrying out the invention it is proposed to form a tearing line, generally indicated at 16, along the edges of the reinforcing and closure strips 15, which will permit of the end sections of the envelope being severed from the body portion thereof when it is desired to remove the contents. In the formation of this tearing line use is preferably made of a pair of cooperating rollers 17 and 18 having teeth 19 and 20 100 about the peripheries thereof, which are arranged in staggered relation with respect to each other and are of gradually increasing depth toward their outer ends so that the outer ends thereof will 105 intermesh, as illustrated in Figure 4. Adjacent edges of these teeth are spaced one from the other about two thousandths of an inch so that as the ends of the envelope are passed therebetween the teeth will 110 not penetrate the sheets forming the envelope and reinforcing strips, but will merely crush the same to form a tearing line in the nature of a crimp, wherein the sheets forming the front 7, bottom flap 10 and the reinforcing strips 15 will be interlocked, as 115 illustrated in Figures 4 and 5. The projecting edges of the teeth of one roller are also inclined or arranged at an angle with respect to the plane of the envelope and also with respect to the projecting edges of the other roller so that the crimps formed by said teeth will increase in depth toward said tearing line. As the ends of the envelopes are passed between the rollers the teeth of 120 the latter slightly overlap the edges of the reinforcing strip 15 so that a portion of the front 7 and bottom flap 10 will also be crimped with the result that after the tearing line has been formed the edges of the 125

130

reinforcing strip will be embedded and interlocked so that a substantially smooth surface along the tearing line will be provided and no edges of the strip will project above the

5 plane of the body of the envelope, thus preventing the possibility of such edges being caught and torn when the envelope is handled in the mails. By reason of the crushing and interlocking of the sheets along

10 the line of the edges of the reinforcing strip, it will be obvious that the contraction of the body of the envelope at these points will form an effective means to prevent the contents of the envelope from moving outward-

15 ly or endwise past the tearing line and beneath the reinforcing strip and thus becoming torn when an end section of the envelope is severed along the tearing line 16.

In actual practice the formation of the 20 tearing line 16 is accomplished simultaneously with the attachment of the transverse edges of the bottom flap 10 to the gummed portions 9, which latter operation is also performed by the rollers 17 and 18.

25 With the gummed portions 9 moistened, it is obvious that by reason of the formation of the teeth 19 and 20 and the extreme contraction of the material at the outer ends of said teeth, the glue will be prevented from 30 passing inwardly beyond the tearing line and onto the inner surfaces of the front 7 and bottom flap 10, thus avoiding the undesirable possibility of these parts adhering to each other after the envelope is made

35 ready for use.

It has been found in actual practice that by forming the tearing line 16 in the manner above described the end sections of the envelope may be easily and quickly severed 40 without tearing any portion of the body of the envelope and that the combined effect of securing the bottom flap to the front by an adhesive and interlocking said portions together with a reinforcing strip 15 provides an effective means for preventing the 45 contents of the envelope from moving outwardly or endwise thereof.

I claim:

1. In an envelope, a body including a 50 front and a bottom flap, a reinforcing strip

folded over adjacent ends of said front and flap, and a tearing line formed by crimping the edges of said strip and the material forming said front and bottom flap, the crimped edges of said reinforcing strip being embedded in and substantially in the same plane with portions of the body which they engage. 55

2. In an envelope, a body including sheets forming front and bottom flaps, a reinforcing strip folded over adjacent ends of said front and bottom flaps, and a tearing line formed adjacent one edge of said body by crimping the material of said flaps and said reinforcing strip along the edges of the latter, the crimps overlapping said edges and extending into said flaps. 60

3. In an envelope, a body portion including a front and a bottom flap, reinforcing strips secured to the ends of said front and said bottom flap, and tearing lines formed along the edges of said body portion by crushing said front, bottom flap and reinforcing strips into interlocking relation. 70

4. In an envelope, a body portion, reinforcing strips secured to the ends of said body portion, and a tearing line extending along an end of said body portion at a distance from the edge thereof, said tearing line being formed by crimping the body portion and reinforcing strip, each crimp increasing in depth from said edge toward said tearing line. 80

5. In an envelope, a body including front and bottom flaps, and a tearing line for said body extending longitudinally of one edge thereof, said tearing line being formed by crimping the material of said flaps into interlocking relation, and each crimp increasing in depth from one end to the other. 85

6. In an envelope, a body including front and bottom flaps, a reinforcing strip secured to said flaps at one end of said body, and a tearing line formed along said end of said body by crimping the material of said flaps 90 and said reinforcing strip, the crimps overlapping the edges of said reinforcing strip and extending into said flaps. 95
